UNITED STATES PATENT OFFICE.

DENNIS J. FLYNN, OF EAST CAMBRIDGE, MASSACHUSETTS, ASSIGNOR OF
TWO-THIRDS TO JOHN S. THOMPSON, OF SAME PLACE, AND THOMAS A.
HUGHES, OF SOMERVILLE, MASSACHUSETTS.

COMBINED DOOR KNOB AND BELL.

SPECIFICATION forming part of Letters Patent No. 668,173, dated February 19, 1901.

Application filed June 29, 1900. Serial No. 22,064. (No model.)

To all whom it may concern:

Be it known that I, DENNIS J. FLYNN, a citizen of the United States, residing at East Cambridge, in the county of Middlesex and State of Massachusetts, have invented new and useful Improvements in a Combined Door Knob and Bell, of which the following is a specification.

This invention relates to new and useful improvements in combined door knobs and bells; and its primary object is to provide a device of this character which shall be simple of construction and the bell of which will be sounded continuously during the revolution of the knob. This device is particularly adapted for use upon the inside of doors, and is especially adapted for use as a burglar-alarm.

The invention consists in providing a semi-spherical knob, which is secured at one end of the spindle of the lock. Mounted upon the flat surface of this knob is a bell of similar form, within which is secured a bracket, pivotally mounted upon which is a knocker. This knocker may be of any desired construction and is connected to a rod which extends through the knob of the spindle and the end of which bears upon a cam, which is secured to the door and which encircles the spindle. The stem is held normally in contact with the cam and is adapted to be reciprocated thereby when traveling thereover. This reciprocation of the rod serves to throw the knocker back and forth into contact with the bell and will obviously cause the same to sound.

The invention also consists in certain features of construction and combination of parts, which will be hereinafter more fully described and claimed, and illustrated in the accompanying drawings, showing the preferred form of my invention, and in which—

Figure 1 is a bottom plan view of the device. Fig. 2 is a central vertical longitudinal section. Fig. 3 is a section on the line 3-3 of Fig. 1.

Referring to the figures of the drawings by numerals of reference, 1 is a spindle, upon the end of which is secured the recessed end 2 of a semispherical knob 3. This knob may be

secured to the spindle in any desired manner. Secured to the center of the flat face of the knob is a bolt 4, upon the outer end of which is mounted a bell 5 of desired form. This bell is provided upon its inner surface with a rib or projection 6, which is adapted to be contacted by the knocker when the device is in operation. A bracket 7 extends from the bolt 4, and pivoted thereto is a lever 8, the outer end of which engages a ring 9, which is secured thereto in any desired manner and which forms the knocker of the bell. This ring is, as shown, loosely mounted upon the end of the lever to permit longitudinal or lateral movement thereof. The inner end of the lever 8 lies within the path of pins 10, which project from the side of the rod 11, which is slidably mounted within the knob 3. This rod preferably passes through a bracket 12, against which bears a coil-spring 13, which encircles the rod and abuts at its opposite end upon the outwardly-turned end 14 of the rod. This spring serves to normally hold said end into contact with the edge of a cam 15, which encircles the spindle, as shown in the drawings, and is secured to the door in any desired manner. A recess 15^a is formed within the under surface of the rod 11, and this is adapted to receive the end of a curved strip 16, which is pivoted to the knob 3 at a point above the recessed portion 2 thereof. This strip normally contacts with the rod when the same is in operation and is adapted to engage the recess when the end 14 of the rod is removed from the path of the cam, thus permitting the said knob to be turned without sounding the alarm.

Brackets 17 extend out from the bolt 4 and are connected by means of springs 18 to opposite sides of the lever 8. These springs are of equal strength and hold the knocker 9 normally in the position shown in Fig. 2.

When the knob is turned from the outside, the uneven surface of the cam 15 will obviously throw the rod 11 back and forth within the knob, causing the pins 10 to throw the knocker away from the projection 6. When said pin escapes the lever, the knocker will be thrown into contact with the rib and ob-

viously sound the bell. If desired, more than one pin, as shown in Fig. 2, may be employed, and in such case it will be seen that two or more strokes of the knocker can be secured 5 upon each in-and-out movement of the rod.

In the foregoing description I have shown the preferred embodiment of my invention; but I do not wish to be understood as limiting myself thereto, as I am aware that changes 10 in the form, proportion, and the minor details of construction may be resorted to without departing from the spirit or sacrificing any of the advantages thereof, and I therefore reserve to myself the right to make such changes 15 as fairly fall within the scope of my invention.

Having thus described the invention, what is claimed, and desired to be secured by Letters Patent, is—

- 20 1. The combination with a spindle having a knob secured thereto; of a cam inclosing the spindle, a bell secured to the knob, a lever pivoted therein, a knocker upon the lever, a rod slidably mounted within the knob 25 and normally contacting with the cam, and means for operating the lever from the rod.
- 2. The combination with a spindle having a knob secured thereto; of a cam inclosing the spindle, a bell secured to the knob, a lever pivoted therein, a knocker thereon, a rod slidably mounted within the knob and normally 30 contacting with the cam, and a pin projecting from the rod and adapted to contact with one end of the lever.
- 35 3. The combination with a spindle having a knob secured thereto; of a cam encircling the spindle, a bell secured to the knob, a pro-

jection therein, a lever pivoted within the bell, a knocker loosely mounted upon one end of the lever, means for holding said knocker normally in alinement with the end of the projection, a rod slidably mounted within the knob and normally contacting with the cam, and a pin upon the rod adapted to contact with and release the lever.

4. The combination with a spindle having a knob secured thereto; of a cam encircling the spindle, a bell secured to the knob, a projection upon the inner surface of the bell, a bracket mounted within the bell, a lever pivoted thereto, a knocker loosely mounted upon the end of the lever, springs for holding said knocker normally in alinement with the end of the projection, a rod slidably mounted within the knob, a spring for holding said rod normally in contact with the cam, and pins upon the rod within the path of the end of the lever.

5. The combination with a spindle having a knob secured thereto; of a cam encircling the spindle, a bell secured to the knob, a lever pivoted within the bell, a knocker loosely mounted thereon, a rod slidably mounted within the knob, means for holding the rod normally in contact with the cam, pins upon the rod in the path of the end of the lever, and a strip pivoted to the knob and adapted to engage a recess within the rod.

In testimony whereof I affix my signature in presence of two witnesses.

DENNIS J. FLYNN.
